G. E. SRACK

SILENT FRICTION GRIP WINDOW LATCH

Filed April 5, 1926

UNITED STATES PATENT OFFICE.

GEORGE E. SLACK, OF TULSA, OKLAHOMA.

SILENT FRICTION-GRIP WINDOW LATCH.

Application filed April 5, 1926. Serial No. 99,702.

My invention relates to friction latches for windows and more particularly to a silent latch that has a friction grip which will hold a window in any desired position as to height; and the object is to provide latches which will be easily operated and positive in action, and which will hold the window at any height even when the sash is loosely mounted in the window casing. Another advantage is that the window can not be unlocked from the outside. Other objects and advantages will be fully explained in the following description and the invention will be more particularly pointed out in the claims.

Reference is had to the accompanying drawings which form a part of this application.

Fig. 1 is a front elevation of a window equipped with the improved latch. Fig. 2 is a broken view of the right side of the sash, showing the tension springs and the bearing strip. Fig. 3 is a view of a flat piece of metal before it is bent to form the bearing strip. Fig. 4 is a view of a flat piece of metal before it is bent to form the gripping member. Fig. 5 is a side elevation of the gripping member. Fig. 6 is an edge view of the same. Fig. 7 is a perspective view of the upper tension spring. Fig. 8 is a perspective view of the lift or handle for raising or lowering the window. Fig. 9 is a horizontal section, taken on the line 9-9 of Fig. 1.

Similar characters of reference are used to indicate the same parts throughout the several views.

The sash frame members 3 and 4 move vertically and freely against the members 1 and 2 respectively. The vertical guide keepers 5 are attached to the window frame in the usual manner but these guide keepers are beveled as shown in Fig. 9. The improved silent friction gripping members 45 are applied to the sash frame and to the window frame to form operative connections, and the object is for adapting the gripping devices for adjusting themselves automatically to gripping positions.

Bearing strips 7 are attached to the sash frame members 3 and 4 and these strips 7 afford the necessary friction for the gripping arms 6. The strips 7 are further made rigid with the sash frame members by angular extensions 8 which are bent at right angles to the strips and countersunk in

the edges of the sash frame. A pressure spring 9 is attached to the bearing strip 7 of each side of the sash frame and secured in place by a tongue or lip 10 which is sprung out of the plane of the body of the extention 8. The springs 9 exert tension and tend to press the sash away from the window frame towards the central part of the window. This tension will make a gripping action against the window frame for locking the sash at different heights. The friction of the spring against the window frame will be sufficient to hold the sash at what ever height desired. It will be understood that the spring on the opposite side of the window functions in the same manner.

A tension or pressure spring 11 is provided for each upper corner of the sash. The lower end of the spring 11 is made stationary with the sash by means of a lug 13 on the spring which is inserted in the slot 12 in the member 8 of the bearing strip. The spring 11 has a socket 14 which receives a lug 15 which is rigid with the grip arm 6. The sash frame is morticed to make provision for swinging or moving the spring 11. The bearing strip 7 has an elongated opening 16 so that the arm 6 will have a limited movement. The object is to make the gripping arm adjustable at the upper end. The arms 6 are pivotally mounted by the lugs 15, it being understood that similar arms 6 are on both sides of the sash. The springs 9 and 11 take care of the lateral movement of the sash.

The inward or outward movement of the sash is taken care of by the angular wings or wedges which are formed on the edges of the grip arms 6. The guide keepers 5 are beveled to make a wedge shape and the members 17 are forced against the guide keepers 5.

For operating these arms 6, they are provided with inwardly projecting extensions 18 at their lower ends. The sash lifts 19 are attached to the base of the sash and the lifts have ears formed thereon and bent down to form guides 20 for the extensions 18 which will move freely behind the ears 20 in their lateral movement. These extensions are provided with operating lugs 21. In operation, grasp the lugs 21 and press them towards the central portion of the sash with sufficient force to overcome the tension of the spring 9 and draw them suffi-

ciently away from the beveled guide keepers 5 and from the sash frame members 3 and 4 and that the friction members 17 so that the gripping arms 6 will release the guide keepers 5. Hold the members 6 free from the guide keepers 5 and the members 3 and 4 while adjusting the sash to the required position. When the desired position for the sash is reached, release the lugs 21. The 10 springs 9 and 11 will force the grip arms 6 against the stops 5 and bearing members 7 and thus grip the sash at the desired elevation. A lug 22 catches on the spring 9. This lug 22 is integral with the grip arm 6 and it 15 constitutes the means by which the grip arm 6 is drawn to operative position by the spring 9. The upper ends of the grip arms 6 are operatively connected to the spring 11 by means of the lug 15 and the socket 14 20 of the spring 11. The spring 11 is prevented from displacement by lugs 23 and 24 struck from the bearing strips 7. The lug 24 acts as a stop or guide against which the socket 14 will stop. The lug 23 is loosely 25 engaged by the grip arm and the tension of the spring is obtained by this lug for adjusting the grip arm 6. The stops 19 are provided with lugs 25 which serve as rests or 30 bearings for the fingers when other fingers engage the lugs 21, in the act of operating the grip arms 6.

What I claim, is,—

1. Friction grip window latches comprising in combination with a window frame and a sash frame, beveled guide keepers attached to said window frame and bearing 35

strips attached to said sash frame, a pair of friction arms operatively connected to said bearing strips at their upper ends and positioned between said guide keepers and said sash frame and provided with wedging members engaging said beveled guide keepers substantially throughout their length, and tension means attached to said bearing strips for forcing said friction arms between 40 45 said stops and the sash.

2. Friction grip window latches comprising in combination with a window frame and a sash frame, beveled guide keepers attached to said window frame and bearing strips attached to said sash frame, a pair of members integral therewith substantially 45 friction arms having elongated wedging throughout their length, said bearing strips having elongated slots in their upper ends, 50 springs attached to said bearing strips and provided with lugs projected through said slots for engaging and holding said friction arms in operative position and for forcing said arms between said guide keepers and friction arms having elongated wedging 55 sash, said arms having lugs near the lower ends thereof, springs attached to the lower ends of said bearing strips for engaging said lugs and co-operating with the lugs of said 60 springs at the upper ends of said strips, and means on the lower ends of said arms for releasing the grip of said arms.

In testimony whereof, I set my hand, this 27th day of March, 1926.

GEORGE E. SRACK.
